(57) **CLAIM**

The ornamental design for an adult toy, as shown and described.

DESCRIPTION

FIG. 1 is a left side view of an adult toy in a first bent state showing my new design;

FIG. 2 is a left side view showing the adult toy in a first bent and stretched state;

FIG. 3 is a left side view showing the adult toy in a second bent state;

FIG. 4 is a left side view showing the adult toy in a second bent and stretched state;

FIG. 5 is a top, front and right side perspective view showing the adult toy in an unbent state;

FIG. 6 is a bottom, rear and left side perspective view of FIG. 5;

FIG. 7 is a front elevational view of FIG. 5;

FIG. 8 is a rear elevational view of FIG. 5;

FIG. 9 is a left side view of FIG. 5;

FIG. 10 is a right side view of FIG. 5;

FIG. 11 is a top plan view of FIG. 5;

FIG. 12 is a bottom plan view of FIG. 5; and,

FIG. 13 is a top, front and right side perspective view showing the adult toy in an unbent and stretched state.

The broken lines in the drawings illustrate portions of the adult toy which form no part of the claimed design.

1 Claim, 13 Drawing Sheets
